CONTAINER

James R. Watkins, Niles Center, Ill.

Application March 9, 1936, Serial No. 67,766

3 Claims. (Cl. 217—48)

This invention pertains generally to containers and particularly to improvements in collapsible containers and methods of making the same.

One of the objects of this invention is to provide 5 in a container having a collapsible tubular portion a new method of manufacturing that portion of the container.

Another object of the invention is to provide a 10 simple and economical method of applying cleats to a flat sheet of scored fibrous material and thereafter fashioning the cleated sheet into a tubular structure having walls that are hinged together at the score lines.

Another object of the invention is to provide 15 a new method of manufacturing a tubular portion of a container to provide interior wall surfaces which are entirely free from seams or other projections.

Further objects and advantages of the invention 20 will become apparent from a perusal of the following description.

In the drawing is embodied certain forms of the invention which have been selected for illustrative purposes only.

25 Fig. 1 is a perspective view of a cleated container having a hinge corner made in accordance with this invention;

Fig. 2 is a horizontal cross-section of the same container on line 2—2 of Fig. 1;

30 Fig. 3 is a sectional view showing the vertical walls of the container of Fig. 1 aligned in collapsed relationship in the position they occupy when the stitching is being applied and at the conclusion of the stitching;

35 Fig. 4 is a sectional view similar to Fig. 3 but embodying the modified hinge corner of Fig. 5, and illustrating how this type of scored corner permits collapsing as shown;

Fig. 5 is a partial sectional view of a modified 40 hinge corner; and

Fig. 6 is a horizontal section of another modified form of the tubular portion of a container embodying this invention.

45 Referring further to the drawing, the invention is illustrated as applied to a collapsible container or crate, that is, one which may be collapsed after manufacture and before use and opened up to receive the merchandise or other articles which 50 it is intended to contain. In the form shown in Figs. 1, 2 and 3, it consists of four walls, 1, 2, 3, 4, which for convenience may be referred to as the side walls of the container. These walls may be made of any thin but inherently stiff material, 55 such as corrugated paper board or solid fiber

board or any other material whose characteristics suit it for use in this invention. Where paper board, either corrugated or plain, is employed, it is preferred that cleats, usually of wood, or other material, be affixed to the outer surfaces of the side walls, as by nailing, gluing, stitching, or other means to reinforce the inherent stiffness of the wall material and cause the wall material and cleats to cooperate with each other to produce a structure of remarkable strength and rigidity, 10 considering the weight and the cost of the materials employed. While the illustrated embodiment discloses three vertical cleats on each side wall, the number of cleats may be varied; and in some instances the cleats may be entirely dispensed with on one or more of the side walls.

The cleats as shown are preferably wooden cleats 5, some of which extend above the top edge of the side wall and some extend below the bottom edge of the side wall as illustrated, so that they may readily be united, by simply nailing to cleats which adjoin them on the top and bottom closure members. The particular arrangement of the cleats is subject to variation, the arrangement shown being selected merely to illustrate 25 one but not the only satisfactory mode of assembly.

The top closure member consists of a sheet of material 6 on which is secured in any suitable manner, as by nailing, gluing, or the like, a plurality of cleats 7 positioned as shown so that when the top closure member is placed in position with its sheet 6 snugly closing the upper end of the container, its cleats will lie in position where they may be nailed to the abutting side wall cleats. 35

The number of cleats employed on the top closure member may, of course, be varied.

A bottom closure member similar to the top closure member is provided and positioned in place and secured similarly to the manner of 40 securing the top closure member.

Various advantages of this collapsible tubular type of container are set forth in my prior Patent No. 1,955,107, issued April 17, 1934. My present invention is an improvement upon that disclosed in my prior patent.

The particular improvement in the construction of the hinge corner which closes the tubular structure will now be described. In making the assembly of side walls and cleats, it is preferred 50 to use a single sheet of fiber board and score it or otherwise render it foldable on the parallel lines 8, 9, 11, and 12, and if desired also at 13 (see Fig. 5), then lay the sheet flatly with the four sections which form the side walls all dis- 55

posed in the same plane. The side wall cleats 5 may then be laid either underneath the sheet or on top of it as desired, depending on whether it is desired to drive the nails or staples through the sheet into the wood or through the wood into the sheet. Preferably the cleats will lie under the sheet and the nails or staples will be driven through the sheet into the wood, see for example the nails 14 in Fig. 2. If the ends of the nails or staples protrude, they, of course, will be clinched over at the same time; and where the side wall cleats are all parallel to each other, as in the present embodiment, the assembly of cleats and single sheet of board may be held in a frame provided for the purpose and passed under a multiple head nailing machine or multiple head stitching machine so that in one passage through the machine all of the cleats will be secured to the four side walls.

Thereafter the walls of the assembly will be collapsed by folding inwardly at the score line 9, whereby the wall 2 will oppose the wall 3 and the wall 1 will oppose the wall 4. This will leave protruding beyond the margins of the cleats adjoining the ends of the sheet of fiber board two free edges of fiber board 15 and 16, which will overlap and preferably register. The fact that it is extremely easy to so score the fiber board and arrange the cleats thereon that an accurate and neat adjustment of these free edges is possible renders their registration easy of accomplishment. In this position, it is a simple matter to pass these two free edges through a stitching machine and stitch them together. The side walls of the container are thus stitched together in a collapsed position and thereafter may be opened up to form the tubular structure. The top and bottom closure members, of course, may readily be formed by stitching, nailing, or otherwise securing their cleats to them, and the entire container may be assembled whenever ready for use. If only a single score 12 is used on one of the projecting ends of fiber board, as shown in Fig. 2, when the four side walls are opened up from the collapsed relationship the portion 16 will extend in the same plane as the side wall 4. When thus constructed the container can be collapsed readily only by swinging walls 1 and 2 toward walls 4 and 3, respectively, about the score lines 9 and 12.

If, however, both projections 15 and 16 are scored as shown in Fig. 5, the structure may be collapsed to bring either walls 4 and 1 into superposed relation or to dispose them in alignment as shown in Fig. 4.

While it is stated and preferred that the projecting ends 15 and 16 be united by stitching, other suitable methods including gluing may be employed.

Ordinarily the width of the projecting portions 15 or 16 will be predetermined so that they may not protrude beyond the thickness of the adjoining cleats or at least not much beyond said cleats so that the stitched hinge corner may always present a neat appearance.

Whenever the width of the side walls, between the parallel hinged edges, is too great to permit the four walls to be extended in a single plane and passed in one movement through the stitching or nailing machine for the purpose of attaching the cleats, I may use two sheets of fiber board to facilitate the manufacture of the container. In such a case, each sheet would be scored at the juncture of two side walls, and also

scored parallel to and slightly spaced from its opposite ends, the cleats applied to each pair of joined side walls and thereafter the two pairs of side walls united by stitching the projecting marginal portions like 15 and 16 at two diametrically opposite corners of the container. In other words, the joining of side walls 1 and 4 as depicted at the lower left corner of Fig. 2 would be duplicated by a similar joining of walls 2 and 3 at the upper right corner of Fig. 2.

Of course, the double reverse scoring shown in Fig. 5 could be used at either or both corners so joined.

One advantage of such alternative method is that large containers may be conveniently assembled in this manner. Also, the two opposite corners so to be stitched may be stitched simultaneously by employing properly spaced apart stitching heads.

Should the size of the container, or other considerations, make it desirable to do so, not merely two corners of the container may be so united, but three of them or all of them may be so joined, and in this event the corner shown in Fig. 5 would be preferred.

Also the method of uniting fiber board corners in accordance with this invention may be utilized in connection with containers having side walls formed of strips or of imperforate sheets of plywood or other material not adapted to be scored or creased and folded back upon itself. Containers of this type are illustrated in my prior United States Letters Patent No. 1,976,693, issued October 9, 1934. When utilizing the present invention in conjunction with the invention of my Patent No. 1,976,693 the fiber board constituting the hinge material, instead of being a single strip at the corner could be two strips such as 17 and 18, each secured to a wall of plywood 19 and 21, respectively, and projecting outwardly and stitched together. A similar joint could be formed by similarly uniting hinge strips 22 and 23, which are secured to plywood walls 24 and 26.

Referring to Fig. 3 it will be seen that in locating the scoring of the fiber board, the score line 9 equally divides the sheet, and while score line 12 is near one margin of the sheet it is, like the other lines, actually the hinge axis of two adjoining walls.

Attention is now called to my prior Patent No. 1,955,107 which shows a method of uniting the four walls to form a tubular container, the overlapping portion of one of the walls being secured to the inner surface of the container wall. The improvement just described in this invention facilitates greatly the ease of uniting the four walls into a single tubular structure after the cleats have been placed thereon, and the cost of accomplishing this operation is tremendously reduced. Furthermore, accuracy of assembly is readily assured under the present improved method.

It also should be stated here that while the heads of the nails 14 are shown for clarity of illustration as not being countersunk, as a matter of practice they are preferably countersunk into the wall material so that there will be no projections on the inner wall surfaces. The improved method of hinging the various walls together, of course, leaves them free of projections, a feature of real importance due to the fact that in using these containers it is customary to place the article on the bottom closure member and secure it thereon if desired, and then drop the

tubular portion of the container down over the article. Smooth interior wall surfaces facilitate this operation.

The final step, of course, is to locate the top closure member in its proper position and then secure by nails, screws or the like, the rigid portions of the end closure members, that is, the cleats thereof, to the cleats of the side walls, completing thereby a remarkably rigid container of light weight and low cost.

It should be understood that the drawing and specification illustrate merely preferred embodiments of the invention and that it is subject to considerable variation and modification without a departure from the spirit and scope of the claims which follow.

Having shown and described my invention, I claim:

1. A collapsible tubular structure comprising a sheet of fibrous material scored to provide a plurality of side walls hinged together at the score lines, said sheet forming one pair of adjoining side walls and having marginal portions which project beyond the corner which they define, with one of said marginal portions being connected to its contiguous wall by a score line reversely scored relatively to the other lines, and means securing said marginal portions together outside of said score line.

2. A collapsible tubular structure comprising

a sheet of fibrous material scored to provide a plurality of side walls hinged together at the score lines, the opposite ends of the sheet parallel to said score lines being secured together outside of the corner of the container which they adjoin, one of said score lines being located parallel to and near one edge of the sheet at said corner to permit the marginal portion of the sheet beyond said score line to be folded at a right angle to the wall of which it forms an extension.

3. A collapsible tubular shipping container structure comprising a body formed of sheet fibrous material to provide four side walls for the structure, two of said side walls at one corner of the structure being extended beyond the corner which they define to provide opposed marginal extensions outside the confines of the structure and one of said marginal extensions being scored on its outer face at the juncture with the wall from which it extends to afford a hinged connection with said wall permitting said extension to assume a position perpendicular to the plane of said wall, and means securing said marginal portions together outside of the container, the walls at the remaining corners of the structure being hingedly connected to enable the structure to be collapsed into flat position.

JAMES R. WATKINS. 30
